Primary Examiner — Wendy L Arminio(74) Attorney, Agent, or Firm — Barry Choobin; Patent 360(57) CLAIM

The ornamental design for a liquor bottle, as shown and described.

DESCRIPTION

FIG. 1 is a perspective view of a liquor bottle, showing my new design;

FIG. 2 is a front view thereof;

FIG. 3 is a rear view thereof;

FIG. 4 is a right-side view thereof; and,

FIG. 5 is a left-side view thereof.

The broken lines depict portions of the liquor bottle that form no part of the claimed design.

1 Claim, 5 Drawing Sheets(56)
